ROCK DRILL

William M. Alexander, Johannesburg, Transvaal,
Union of South Africa, assignor to Sullivan
Machinery Company, Claremont, N. H., a cor-
poration of Massachusetts

Application December 31, 1937, Serial No. 182,726
In the Union of South Africa February 4, 1937

2 Claims. (Cl. 121—10)

This invention relates to rock drills, and more particularly to improved hole cleansing means for a hammer rock drill for conducting cleansing liquid to the bottom of the drill hole to cleanse the cuttings therefrom.

In the drilling of rock, particularly underground in mines, when compressed air or a mixture of air and liquid is delivered by means of the conventional hole cleansing means of the rock drill to the bottom of the drill hole to cleanse the cuttings from the hole, there is great danger of silicosis. This pathological condition of the lungs is receiving a great deal of attention from the health departments and legislative bodies of government units. This condition of the lungs is attributed to the action of the siliceous stone dust on the lung tissue, it is believed, and the risk of harm is believed to be greatly increased when water vapor maintains the rock dust in suspension, as occurs when compressed air and water both pass down the drill hole and the air in its expansion and blowing tends, as it were, to atomize the water and produce a mist or fog which maintains the stone dust in suspension in the air and perhaps increases its ingress to the lungs of the drill runner. Various devices to overcome this condition have been attempted, such as water boxes, vacuum devices, and the like, to eliminate the danger of silicosis, but complete success has not been attained.

An object of this invention is to provide an improved hole cleansing means for a rock drill which, to a substantial extent, eliminates the danger of silicosis. Another object is to provide an improved rock drill hole cleansing means for effecting hole cleansing by the use of a liquid jet while precluding the entrance of compressed air to the drill hole. It is a further object to provide improved means for venting the compressed air from the drill steel chuck of a rock drill so only liquid is conducted to the bottom of the drill hole. A further object is to provide in a rock drill of the above character a novel arrangement of vent passages for the drill steel chuck. Yet another object is to provide improved deflecting means associated with the vent passages for laterally deflecting the air issuing from the vent passages. These and other objects and advantages of the invention will, however, hereinafter more fully appear.

In the accompanying drawing, there is shown for purposes of illustration one form which the invention may assume in practice.

In this drawing—

Fig. 1 is a view in longitudinal vertical section

through a hammer rock drill with which an illustrative embodiment of the improved hole cleansing means is associated.

Fig. 2 is an enlarged cross sectional view taken substantially on line 2—2 of Fig. 1.

Fig. 3 is a detail sectional view in perspective showing the improved drill steel chuck.

In this illustrative embodiment of the invention there is shown a rock drill generally designated 1 with which is associated the improved 10 hole cleansing means generally designated 2. The rock drill is herein of the pressure fluid actuated hammer type comprising a cylinder 3 having a bore 4 containing a reciprocatory hammer piston 5. The hammer piston has a forwardly projecting striking bar 6 guided at 7 in a bushing 8 supported within a front motor head 9, and the piston striking bar is adapted to deliver impact blows to the shank of a drill steel 10 as will later be described. A pressure fluid actuated distributing 20 valve mechanism 11 is mounted in a valve box 12 arranged at the rear end of the motor cylinder, and this distributing valve is adapted to control the supply of pressure fluid through suitable passage means to the motor cylinder to 25 effect reciprocation of the hammer piston in the manner well known to those skilled in the art. Conventional means is provided for rotating the drill steel as it is percussively actuated by the hammer piston, comprising a ratchet and 30 pawl mechanism 13 having a spirally grooved rifle bar 14 slidably interlocked with a rifle nut 15 secured within the hammer piston. As the hammer piston moves forwardly, the pawls of the ratchet and pawl mechanism permit the 35 rifle bar to rotate so that the hammer piston delivers an unimpeded blow to the shank of the drill steel, and upon the return movement of the hammer piston, the rifle bar is held against rotation by the pawls, and, due to the spiral groove connection between the rifle bar and piston, the piston is caused to rotate. The rotary motion of the piston is transmitted to the drill steel through straight flutes 16 formed longitudinally on the piston striking bar and slidably interlocked with straight lugs 17 formed on a chuck 40 nut 18 secured within a chuck sleeve 19. This chuck sleeve is rotatably mounted within a front chuck housing 20 and has secured thereto a chuck bushing 21 in which the shank of the drill steel 10 is mounted. It will thus be seen that as the hammer piston reciprocates to actuate percussively the drill steel, the latter is at the same time intermittently rotated.

Now referring to the improved hole cleansing 55

means for admitting only liquid to the bottom of the drill hole, it will be noted that secured, as by a gland plug 22, within the back head 23 of the motor cylinder is a liquid conducting tube 24 to which liquid under pressure is supplied through a pipe connection 25 from any suitable source of liquid supply. This liquid conducting tube extends axially through alined bores 26 and 27 formed in the rifle bar and hammer piston 10 respectively and at its forward end slidably fits an axial bore 28 formed in the drill steel 10. The forward end of the liquid conducting tube has a tight sliding fit with the drill steel bore. In order to comply with certain regulations it may be desirable to terminate the liquid conducting tube 24 short of the shank of the drill steel 10 instead of extending it thereinto. In this illustrative construction the shank of the drill steel 10 has a reduced cylindrical portion 29 at its rear end, and this reduced shank portion is machined to have a tight sliding fit and is slidably guided in a wear and shank-centering washer or ring 30 supported within the chuck sleeve 19, this wear washer being mounted in the chuck sleeve bore and held between a shoulder provided by an inwardly directed flange 31 formed on the chuck sleeve and the rear end of the chuck bushing 21 in the manner shown in Figure 1. The chuck sleeve 19 has formed therein a chamber 32 within which the rear end of the drill steel shank projects in a position to receive the impact blows of the piston striking bar, and the latter is adapted to move, as the piston reciprocates, through the chuck sleeve and an alined bore 33 communicating with the chamber 32, into this chamber. In this improved construction, the chuck sleeve 19 is provided with an annular series of vent holes 34 each formed longitudinally through the body of the chuck sleeve and opening at their rear ends within the chamber 32 and at their front ends at the forward face of the chuck sleeve. Due to the vent holes 34 extending longitudinally within the body of the chuck sleeve 19, the external surface of the chuck sleeve presents a substantially unbroken surface which facilitates the lubrication thereof. There is provided near to and in front of the forward ends of the vent holes 34 an external flange 35, herein formed integral with the chuck bushing 21, this flange having a curved deflecting surface 36 for laterally deflecting the air as it is vented from the chamber 32 through the vent holes 34. It will thus be seen that any compressed air as it flows from the bore of the motor cylinder through the flutes 16 in the striking bar and through the chuck sleeve and the bore 33 to the chamber 32, is vented to atmosphere through the vent holes 34 so that the building up of any substantial air pressure at the rear end of the drill steel shank is prevented. The provision of the lateral deflecting flange 35 prevents the blowing of compressed air through the longitudinal vent holes 34 toward the mouth of the drill hole, thereby further preventing the agitation of any rock dust which might be present at the mouth of the drill hole. If desired, by placing the flutes of the striking bar in alinement, more or less, with the vent holes 34 through the chuck sleeve, an aspirator effect is produced which results in the provision of an actual suction effect at the rear end of the drill steel shank for further insuring the prevention of passage of compressed air through the drill steel bore to the bottom of the drill hole. Advantageously, the bore 33 is large in radial di-

5 mension as compared with standard practice, in order to insure adequate flow area; and the rear ends of the vent holes 34 may be sloped inward towards the axis so as to bring their rear orifices substantially into alinement with the flutes 16 in the sense that both are at about the same radial distance; the radius of the bore 33 being preferably not less than the radial distance of the rear orifices of the vent holes 34.

10 As a result of this invention, it will be noted that an improved rock drill hole cleansing means is provided wherein the admission of compressed air through the drill steel to the bottom of the drill hole is entirely eliminated, due to the improved venting arrangement of the chuck sleeve 15 chamber at the rear end of the drill steel shank. It will further be noted that by the provision of the improved arrangement of the chuck venting means water under pressure is supplied to the drill hole to cleanse the cuttings from the hole 20 while the entrance of compressed air to the drill hole is absolutely precluded. It will still further be evident that the improved hole cleansing means, due to its simple nature, may be readily applied to a conventional rock drill with a 25 minimum of change and expense. Other advantages of the improved hole cleansing means will be clearly apparent to those skilled in the art.

30 While there is in this application specifically described one form which the invention may assume in practice, it will be understood that this form of the same is shown for purposes of illustration and that the invention may be modified and embodied in various other forms without departing from its spirit or the scope of the appended claims.

35 What I claim as new and desire to secure by Letters Patent is:

1. In a rock drill hole cleansing means, the 40 combination with a rock drill having a chuck formed with a bore, and a chuck bushing mounted in said chuck bore for receiving and supporting the shank of a hollow drill steel, the chuck having a chamber within which the rear end of 45 the drill steel shank projects in a position to receive the impact blows of the drill hammer piston and into which chamber pressure fluid flows from the motor cylinder of the drill past the piston striking bar as the hammer piston 50 percussively actuates the drill steel, of means for venting said chamber to atmosphere to prevent the building up of a substantial pressure at the rear end of the drill steel shank, comprising a series of longitudinal vent passages formed in 55 and extending lengthwise of said chuck externally of said chuck bushing, said vent passages formed in the chuck between the walls of the chuck bore and the exterior surface of the chuck, said bent passages opening at their rear ends in 60 said chamber and at their forward ends at the front end of the chuck.

65 2. In a rock drill hole cleansing means, the combination with a rock drill having a chuck formed with a bore, and a chuck bushing mounted 65 in said chuck bore for receiving and supporting the shank of a hollow drill steel, the chuck having a chamber within which the rear end of the drill steel shank projects in a position to receive the impact blows of the drill hammer 70 piston and into which chamber pressure fluid flows from the motor cylinder of the drill past the piston striking bar as the hammer piston percussively actuates the drill steel, of means for venting said chamber to atmosphere to pre- 75

vent the building up of a substantial pressure at the rear end of the drill steel shank, comprising a series of longitudinal vent passages formed in said chuck externally of said chuck bushing, said vent passages extending lengthwise of the chuck and formed in the chuck between the walls of the chuck bore and the exterior surface of the chuck, said vent passages opening at their rear ends in said chamber and

at their forward ends at the front end of the chuck, and means arranged at the front end of the drill steel chuck and against which the pressure fluid discharged from said vent passages impinges for deflecting the pressure fluid discharged from said vent passages in a lateral direction with respect to the drill. 5

WILLIAM M. ALEXANDER.

CERTIFICATE OF CORRECTION.

Patent No. 2,217,535.

October 8, 1940.

WILLIAM M. ALEXANDER.

It is hereby certified that error appears in the printed specification of the above numbered patent requiring correction as follows: Page 2, first column, line 10, for "slidably" read --slidingly--; and second column, line 60, claim 1, for the word "bent" read --vent--; and that the said Letters Patent should be read with this correction therein that the same may conform to the record of the case in the Patent Office.

Signed and sealed this 12th day of November, A. D. 1940.

Henry Van Arsdale,
Acting Commissioner of Patents.
